(57) **CLAIM**

The ornamental design for an energy storage system as shown and described.

DESCRIPTION

FIG. 1 is a front top perspective view of an energy storage system showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is an enlarged view of the encircled portion 8 indicated in FIG. 1; and,

FIG. 9 is an enlarged view of the encircled portion 9 indicated in FIG. 2.

The evenly dashed broken lines depict portions of the energy storage system that form no part of the claimed design. The unevenly dashed broken lines in FIGS. 1, 2, 8, and 9 indicate the area shown in the enlarged views in FIGS. 8 and 9 and form no part of the claimed design.
